UNITED STATES PATENT OFFICE.

GEORGE F. FIFER, OF PROVIDENCE, RHODE ISLAND, ASSIGNOR TO CHARLES N. RICHARDSON,
OF PROVIDENCE, RHODE ISLAND.

CONSTRUCTION OF FIRE-EXTINGUISHER TANKS.

No. 922,118.

Specification of Letters Patent.

Patented May 18, 1909.

Application filed September 9, 1907. Serial No. 392,059.

To all whom it may concern:

Be it known that I, GEORGE F. FIFER, a citizen of the United States, residing at Providence, in the State of Rhode Island, have invented a new and useful Improvement in the Construction of Fire-Extinguisher Tanks, of which the following is a specification.

The nature of my invention consists in an improved construction whereby the curved discharge pipe of the tank may be made removable instead of being permanently soldered to the head of the tank as heretofore, and a stronger joint be provided between the said pipe and the head of the tank.

In the accompanying drawings:—Figure 1 represents a vertical axial section of the fire extinguisher tank, Fig. 2, represents a transverse section taken in the line 2, 2, of Fig. 1. Fig. 3, represents an enlarged side view of the removable curved discharge pipe of the tank. Fig. 4, represents an enlarged side view of the flanged sleeve which is secured to the hemispherical head of the tank. Fig. 5, represents a detail top view of the discharging end of the tank.

In the drawing, A represents a cylindrical fire extinguisher tank provided with the hemispherical heads B and C, and with the opening D through which the receptacle for holding the acid for producing the gas is inserted, the said opening being then tightly closed by means of a suitable cover.

To the inner side of the hemispherical head B, is secured the sleeve E, by means of the oblique curved flange F, which is firmly riveted to the inner side of the head B, and then soldered to form a tight joint. The sleeve E is provided with the stuffing box M, by means of which a tight joint is formed around the removable discharge pipe G, the said discharge pipe being provided at its outer end with the valve H, and with the hose

attaching pipe I, and at its closed inner end with the perforations J. The perforated end 45 of the said pipe is removably held in position by means of the retaining checks K K, soldered to the inner side of the tank at each side of the pipe G as shown in Fig. 2 to prevent the said pipe from turning in the stuffing box M. The pipe G is provided with a projecting shoulder N at its side in order to hold the said pipe in proper position in the chamber of the tank.

Whenever it is desired to remove the discharge pipe from the tank, the valve H is to be first removed from the said pipe together with the gland L of the stuffing box M, then the said discharge pipe G may be withdrawn from the sleeve E and removed through the 60 opening D in the body of the tank.

As heretofore constructed the discharge pipe G has been soldered direct to the head B, and has not been removable, hence the manifest difficulties of making repairs, and 65 by the employment of the flanged sleeve a much stronger joint is made between the said pipe and the hemispherical head of the tank.

I claim as my invention:—

The combination of a cylindrical fire extinguisher tank provided with hemispherical heads, with a sleeve having an oblique curved flange secured to the hemispherical surface of one of the said heads, the stuffing box in the 75 bore of the said sleeve, a removable discharge pipe passing through the said stuffing box and curved to the opposite side of the chamber of the tank, and means for chocking the inner end of the said discharge pipe to prevent turning movement of the said pipe within the said stuffing box.

GEORGE F. FIFER.
